United States Patent

Des. 238,704

Patented Feb. 3, 1976

238,704

RADIO RECEIVER

Kikuo Ohta, Katano, Japan, assignor to Matsushita
Electric Industrial Co., Ltd., Kadoma, Japan

Filed Jan. 9, 1974, Ser. No. 431,971

Claims priority, application Japan Aug. 14, 1973

Term of patent 14 years

Int. Cl. D14—03

U.S. Cl. D56—4 B

FIG. 1

FIG. 2

FIG. 1 is a front, top and right side perspective view of a radio receiver showing my new design; and

FIG. 2 is a rear, bottom and left side perspective view.

The grooves on the framing wall around the front left symmetrical circular dial are continuous around this wall.

I claim:

The ornamental design for a radio receiver, as shown and described.
